FOLDING STAIRWAY

Reinhold B. Marschke, St. Paul, Minn.

Original application August 19, 1940, Serial No. 353,164. Divided and this application December 18, 1941, Serial No. 423,474

5 Claims. (Cl. 228—50)

This invention relates to folding stairways which include a substantially rectangular frame and are provided with a stairway section in said frame. The stairway is made sectional so that one section of the stairway will fold against the other section to permit the stairway to be folded into a compact state so that it will fit within the rectangular frame in the ceiling of a building. The stairway sections are adapted to be extended in a manner to form a continuous stairway from one floor to another in a building.

This application is a division of application filed August 19, 1940, Serial No. 353,164, for "Folding stairways."

It is a feature to provide a unitary structure which includes the rectangular casing, the foldable stair sections and the lever and spring means adapted to cause the stair sections to fold in a compact state and when folded to lie within the rectangular frame which holds the stairway together as a unit. Thus my stairway may be made up in a unit structure, completed at the factory where it is manufactured, and shipped to the customer in complete form so that all that is necessary to install the same is to provide an opening between the floors where the stairway is to operate and in the ceiling of the building, and then by securing the rectangular frame in position in said opening, the stairway will be ready for use.

It is also a feature to provide a foldable stairway having a series of sections, one section of which is secured at one end to the frame which surrounds and holds the stairway when it is folded, and to provide a pair of levers pivotally secured at one end to the frame and at the other end pivotally and slidably secured to the stairway section. I also provide a pair of arms pivotally secured to the levers and pivotally connected to a spring urged arm means which rotates in a manner to wrap the spring thereabout, increasing the tension of the spring when the stairway is extended and rotating in the opposite direction when the stairway is closed, thus providing the increased spring tension for lifting the stairway when it is extended and decreasing the spring tension when the stairway is in folded position and stored out of the way in the rectangular frame.

These features together with other details and objects will be more fully and clearly hereinafter set forth.

The drawings illustrate in Figure 1 the rectangular unitary frame with the foldable stairway enclosed within the frame, showing the same 50

in perspective looking up toward the bottom and closure of the stair unit.

Figure 2 illustrates in perspective the stairway unit partially unfolded.

Figure 3 illustrates in perspective the stairway unit completely unfolded and ready for use.

Figure 4 illustrates a detail of a portion of the stairway sections, levers and operating spring, showing the position thereof when the stairway 10 is in complete folded position within the casing.

Figure 5 is a view similar to Figure 4, showing the stair sections partially separated and the relative position of the side levers and spring associated therewith.

Figure 6 is a detail of a portion of the stair, showing the side operating levers and spring and showing the stair sections extended in full open position.

Figure 7 is a detail of a portion of the stair 20 sections in closed position, and showing the balancing levers with the cam head secured thereto and the spring operating in conjunction with the levers and the cam head.

Figure 8 is a similar detail to Figure 7, showing 25 the parts in partially opened position and illustrating the manner in which the spring wraps around the cam head as the cam head moves from closed toward open position.

Figure 9 is a similar detail to Figures 7 and 8, 30 showing the balancing levers, the spring, and the cam head in the approximate position of the same when the stair sections are in full open or in practically full open position.

In my unitary folding stairway I provide a 35 rectangular casing 10 which encloses the stairway A when the same is folded and the bottom cover 11 is in closed position as illustrated in Figure 1.

My stairway A is made up in complete form 40 with the rectangular casing 10 which is adapted to support the folding sections 12 and 13 of the stairway within the same. When the stairway is folded the closure 11 acts to close or conceal the stairway sections 12 and 13 from below. The cover 11 may act as a ceiling closure when the casing 10 is positioned within a rectangular opening formed in the ceiling of the building and the casing 10 is secured in position to hold the stairway A in place in said opening.

The section 12 of the stairway A carries the cover or closure 11 along the bottom of this stairway section and the upper end of this section is pivotally secured at 14 on each side to the casing 10.

The folding stair A has its bottom section 13

connected with the upper section 12 by a pair of pivoted levers 16 on each side of the same which connect the upper section 12 and the lower section together. The levers 16 are pivoted at one end at 17 to the section 13 and are pivoted together at 18 so as to fold into the position illustrated in Figures 4 and 5 when the stairway is folded together and to extend in the position illustrated in Figure 6 when the stairway is stretched out as is also illustrated in Figure 3.

Coil springs 19 engage the free end of the levers 16 and these springs extend under the rollers 20 which hold the coil spring extending under the treads of the stair section 12. The coil springs 19 extend on either side of the respective sections 12 and 13 and when the sections are extended the lower section 13 locks by means of the shoulder 22 in the notch 23 to provide with the levers 16 the necessary rigidity to hold the lower section 13 extending from the upper section 12 as illustrated in Figure 3.

By pulling on the lower section 13 and removing the shoulder 22 from the notch 23, the arms 16 and springs 19 will act to pull the stairway section 13 up into folding position.

Balancing levers 25 and 26 are provided for the folding stairway A, the levers 25 and 26 being pivoted together at 27 and the levers 25 being pivoted to the sides of the casing 10 at 28 on one end. The other ends of the levers 25 are pivotally and slidably connected by means of the rollers 29 which roll in the longitudinal tracks 30 secured to the stringers of the section 12 of the stairway.

The lever 26 has one end pivotally connected at 31 to the arm 32, which arm is rigidly secured to a cam block 33. The arm 32 is pivotally connected at 34 to the side of the casing 10. Balancing coil springs 35 have one end attached at 36 to the cam block 33 and lever 32, while the other end of these coil springs 35 are connected to the casing 10, not shown. Thus when the stairway is moved into folded position the cam block 33 and the levers 25 and 26 will be in the position illustrated in Figure 7. It will be noted that the pivot point 31 extends slightly to the left of the pivot point 34 so that when it is desired to open the stairway A, the hook 37 which is secured to the cover 11 as illustrated in Figure 1, is engaged and with the downward pull on the cover 11, the cams 33 are caused to rotate on the pivot point 34, winding one end of the spring 35 around the same to automatically increase the spring tension as the stairway A opens up, and thus providing a balancing spring cam and lever means for operating the stair to permit the same to be easily lifted into closed position.

It will be apparent that any style of section 13 may be attached to the section 12 of my folding stairway so that the section 13 may be secured to the section 12 in any suitable manner which permits the section 13 to fold up onto the section 12 before the section 12 is lifted by the levers, cam and spring means into closed position. It will also be apparent that a tension remains on the cam 33 by reason of the spring 35 to hold the cover 11 closed under spring tension.

The easy operation of my stairway together with its unitary structure and the simple cam, lever and spring means which provide a balancing means for my stairway, permit me to make my stairways in an economical manner, yet they are strong and durable to provide a stairway in the attic of a building, or from one floor to

the other, all of which is concealed when the stairway is closed. In a stairway of this character it is of primary importance that the same be made economically so that people can afford to use the same in buildings and homes where they are required.

In accordance with the patent statutes I have described the principles of my stairway, together with the details of construction thereof, and I desire the patent to be interpreted within the scope of the following claims or the equivalents thereof.

I claim:

1. A folding stairway including a rectangular frame for enclosing the same, stairway sections pivotally secured at one end to said frame and connected together in a manner to fold into a compact state within said rectangular frame, a pair of levers pivotally secured at one end to said frame and at the other end pivotally and slidably secured to said stairway section, a pair of arms pivotally secured at one end to said levers and pivotally secured at the other end to a pair of cam levers, said cam levers pivotally connected to said frame, a cam member on each of said cam levers, spring means for urging said cams to rotate said levers in one direction by the tension of said spring means, whereby as said stairway is opened, the tension on said spring means will increase to provide a balancing operating means for said stairway.

2. A folding stairway including stairway sections pivotally and slidably connected together, a rectangular frame for receiving said stair sections when they are folded, a closure secured to one of said sections to close said stairway from below when folded, a pair of levers pivotally and slidably secured to the sides of said upper stair sections and pivoted to the insides of said rectangular frame, a pair of links pivotally connected at one end to said levers and pivotally connected at the opposite end to a pair of cam arms, cam members rigidly secured to said cam arms, said cam arms pivotally secured to said frame, coil springs adapted to wrap around said cam members as the stairway sections are opened, and to unwrap from said cam members when the stairway sections are closed to provide a spring and lever balancing means for said stairway in the operation of the same.

3. A unitary foldable stairway in combination with a casing for enclosing and supporting the same, comprising an upper stairway section having one end pivoted to said casing, a pair of balancing levers on either side of said upper stairway section having one end slidably and pivotally connected thereto, pivot means for attaching said pair of levers inside of said casing, said balancing pair of levers including a secondary lever pivoted at one point between the ends of the levers which are slidably connected to the upper stairway section and having the other end of said pair of levers pivotally connected to a pair of cam arms, means for pivoting said cam arms to said casing, a cam member on said cam arm, and a balancing spring adapted to be wrapped and unwrapped around said cam in the operation of said stairway to provide a spring balancing means for said foldable stairway.

4. A folding stairway comprising a substantially rectangular frame, a stairway section pivotally secured at one end to said frame, a pair of levers pivotally secured at one end to said frame and at the other end pivotally and slid-

ably secured to said stairway section, a pair of arms pivotally secured to said levers at one end and pivotally secured at the other end thereof to a pair of cam arms, said cam arms pivotally secured to said frame, a cam member on each of said cam arms, and balancing springs adapted to be wrapped and unwrapped around each of said cam members in the operation of said stairway to provide a spring balancing means for said folding stairway.

5. A sectional stairway for buildings including a substantially rectangular casing for enclosing said stairway when it is folded, foldable stair sections, means for pivotally and slidably supporting one of said sections in relation to the other of said sections, the other of said sections

being adapted to support a closure on the bottom thereof which acts to conceal the stairway when it is folded, and said other section being adapted to be pivotally connected on one end to said rectangular casing and being slidably and pivotally connected to a pair of balancing lever means which are pivoted to said casing, a pair of links pivoted to said balancing levers at one end thereof and pivoted at the other end to a pair 10 of cam arms, said cam arms being pivoted to said casing, a cam member secured rigidly to each of said cam arms, and a pair of coil springs adapted to wrap around each of said cam members to increase the tension on said springs when sections 15 of said stairway are extended into open position.

REINHOLD B. MARSCHKE.
